HEEL ATTACHING MACHINES

Chester E. Rogers, Jr., Beverly, Mass., assignor to United Shoe Machinery Corporation, Flemington, N.J., a corporation of New Jersey

Filed Dec. 7, 1962, Ser. No. 242,942

14 Claims. (Cl. 1—335)

This invention relates to machines employed for the attachment of a heel to a shoe of the type illustrated and described in United States Letters Patent No. 2,428,047, granted September 30, 1947, to John F. Standish, and, more particularly, to the increased automation of such machines.

Heretofore, in machines of this type, the operator was required to perform a number of physically taxing operations requiring precise positioning of the shoe and heel thereon and of various members of the machine. In the most advanced machines of this type prior to the present invention, the operator manually had to shift the work supporting member or jack from a work receiving position to an operative position. Failure of the operator properly to position the work supporting member in operative location resulted not only in improper nailing but also in possible breakage of the driving spindle due to the misalignment of the operative members. Further, the heel would not be securely held in the correct position on the shoe as a result of the incompatible positioning of the work supporting member and the holdown means. The operator was additionally required to initiate the movement of the holdown means into operative location while physically retaining the shoe and heel thereon in position on the supporting jack, this step occurring subsequent to shifting said jack into operative position.

Accordingly, the principal object of the present invention is to provide a fully automatic heel attaching machine which requires only that the operator initially place a shoe and heel to be secured thereto in position and initiate and maintain the sequential positioning of certain members of the machine in operative location by the depression of an actuating treadle. The operator is thereby relieved of the tiring and time-consuming operations noted above and, consequently, the efficiency, consistency, and accuracy of the machine are increased. The operator is given complete control of the sequential movement of the members of the machine into operative positions and of the actual insertion of the securing device and, therefore, is able to stop the machine if one of the members is not properly located.

A correlative object to that noted above is to provide means for automatically shifting the work supporting member or jack from a work receiving position to an operative position whereby certain instrumentalities of the machine are placed in position to facilitate the insertion of a securing device.

A further object of this invention is to provide a pivotal work supporting jack which can be located in a work receiving position which facilitates the positioning of a shoe thereon.

To this end and in accordance with a feature of this invention, there is provided a heel attaching machine having means for automatically shifting the work supporting member or jack from a work receiving position to an operative position, means for automatically positioning the holdown device in position to engage the heel of a shoe mounted on said jack in response to the presence of said jack in operative position, means for moving the holdown device into engagement with said heel, and means for inserting a nail through the heel seat of the shoe into the heel positioned thereon.

The above and other features of the invention, together with various novel details of construction and combina-

2

tions of parts, will now be more particularly described in connection with an illustrative machine in which the invention is embodied and with reference to the accompanying drawings thereof in which:

5 FIG. 1 is a view in front elevation of a machine exemplifying the invention, certain frame portions being cut away to reveal internal mechanisms;

FIG. 2 is an enlarged view, partly in section, of the nail driving instrumentalities;

FIG. 3 is a view in side elevation of the machine illustrated in FIG. 1, certain frame portions being cut away to reveal internal mechanisms;

FIG. 4 is a view in side elevation showing the jack in the work receiving position taken along the line IV—IV of FIG. 1;

FIG. 5 is a view in side elevation showing the jack in operative position;

20 FIG. 6 is a view of certain of the positioning means showing the location thereof when the jack is in operative position;

FIG. 7 is a view in side elevation showing the relative location of the operative members during the insertion of a nail;

25 FIG. 8 is a view of certain of the positioning means showing the location thereof when the hood is in engagement with a heel;

FIG. 9 is an enlarged view of the cam rods showing the position thereof in the operative position;

30 FIG. 10 is a view in side elevation, partly in section, of a jack having a shoe thereon mounted on a last having a spindle receiving passage disposed at an angle to the last pin receiving thimble;

FIG. 11 is an enlarged view of the spindle and mounting means therefor showing a sleeve on said spindle;

35 FIG. 12 is a plan view of the jack in the work receiving position;

FIG. 13 is an enlarged view, partly in section, of the spindle and the mounting means therefor taken along the line XIII—XIII of FIG. 12;

40 FIG. 14 is a view in perspective, partly in section, showing certain of the spindle support means;

FIG. 15 is a sectional view taken along the line XV—XV of FIG. 12;

45 FIG. 16 is a view of the cam rods and spindle mounting in the work receiving position; and

FIG. 17 is a diagrammatic view of the fluid system.

The frame of the machine comprises a base portion 10 and a housing 12 secured to said base portion. A hood or head 14 is mounted on the housing 12 for movement relative to nail inserting instrumentalities, as hereinafter described.

50 The illustrated machine is hereinafter described with reference to the attachment of a heel 16 (FIGS. 4, 5, 7 and 10) to a shoe 18 by the use of a drive screw or nail 20 which is driven through the heel seat of the shoe and into the heel. As explained in Letters Patent of the United States No. 3,101,480, issued August 27, 1963, in the name of Chester E. Rogers, it is common practice to attach the heel 16 temporarily to the shoe by the drive screw 20, said heel being attached permanently to the shoe after the last has been removed therefrom.

55 A work supporting member or jack 22 (FIGS. 1, 3, 4, 7, 10 and 12) is pivotally mounted on the upper portion of the housing 12 by means of rods 24, 24 (FIG. 15) mounted in bearings 26, 26 secured to the housing 12 and extending into a carrier 28 upon which the jack 22 is carried, said rods being retained in position in the carrier by set screws 30, 30. The carrier 28 extends rearwardly from the pivot point determined by the rods 24, 24 and has drive means attached to the rearward portion thereof, as hereinafter described. The jack is thus pivotal about the bearings 26, 26 between an upper work receiving posi-

tion and an operative position. When the jack is located in its work receiving position, as illustrated in FIGS. 1, 3 and 4, positioning of a last 40 thereon is easily accomplished as a result of the operator's ready access thereto. The work supporting member 22 comprises a hollow spindle 42 and means for carrying the same, a mount 44, means for locking the spindle against movement and for permitting movement of the mount when the jack is in the last receiving position, and means responsive to the movement of the jack from the work receiving position to the operative position for freeing the spindle and restraining the mount. The spindle and the mountings therefor are carried on the carrier 28 and extend through a central cavity therein.

An upstanding housing portion 45 of the carrier 28 has projecting rearwardly therefrom a pair of spaced flanges 46, 46 forming abutments for a guide block 48 (FIGS. 3, 4, 5, 7, 10, 11, 13, 14 and 16) which is journaled on a pair of bearing pins 50, 50 extending through the carrier 28 (FIG. 13) on opposite sides thereof and retained in position therein by set screws 52, 52. The guide block 48 extends through the cavity in the carrier and has a cylindrical bore or guideway 54 extending longitudinally thereof. The guide block has a pair of recesses 55, 56a (FIGS. 5, 10, 13 and 16) adapted fittingly to receive an end of a plunger 60 which is slidably mounted in a guideway 62 (FIG. 13) in one of the flanges 46 of the carrier 28 and is constantly urged inwardly by a spring 64. The angular setting of the guide block 48 upon the carrier 28 about the common axis of the bearing pins 50, 50 may be quickly effected by the engagement of the plunger 60 with one or the other of the recesses 55 or 56a. The spindle 42 is slidable in the guideway 54 and, thus, the relative position thereof with respect to the mount 44 can be determined by adjustment of the angular setting of the guide block 48. As more fully described in the aforementioned patent, this facilitates the adaptation of the work support member to accommodate lasts having passageways extending through the last at different angles to the general plane of the rim of the heel plate of the last.

A driver 70 is mounted in the hollow spindle 42 for reciprocation. The spindle 42 comprises upper and lower cylindrical portions 72, 74 of relatively small and large diameter and a beveled portion 76 joining said upper and lower cylindrical portions. The spindle 42 is adapted to fit slidably in a passage 78 in a last 79 positioned rearwardly of the usual last pin receiving thimble and disposed at an angle thereto, as illustrated in FIG. 10, and is constantly urged upwardly by a tension spring 80 upper and lower ends of which are attached to studs secured respectively to the guide block 48 and to a foot 84 which is clamped upon the lower end portion of the spindle by a screw 86. Upward movement of the spindle 42 in the block 48 is limited by the engagement of the upper face of the foot 84 with the lower face of the block. Adjustment of the foot 84 on the spindle 42 permits the upper extremity of the spindle to be located at the proper height to support the shoe on the last in a definite relation to the driver 70.

As illustrated in FIG. 4, the spindle 42 is sometimes inserted into a passage 88 formed by a last pin receiving thimble 90 and an extension thereof in a last of the type designated by the reference 40. The passage 88 commonly has a slightly greater diameter than the passage 78 in the last 79. In operating upon a shoe mounted on the last 40, a sleeve 92 (FIGS. 3, 4, 5, 7, 11, 13 and 16) is mounted on the upper cylindrical portion 72 of the spindle 42 and has a flanged lower end 94. When the flanged lower end 94 of the sleeve 92 engages the upper end of the bevel portion 76 of the spindle 42 the upper end of the sleeve is flush with the upper end of the spindle, the outside diameter of the sleeve being such that it fits slidably in the passage 88 of the last 40.

In order to insure that the sleeve 92 is held in its proper

position on the spindle 42 there is provided a latch in the form of a lever 100 which is journaled on a pin 102 secured to the block 48 and has its upper end overlying the flanged lower end 94 of the sleeve. A spring 104, opposite ends of which are housed in recesses in the block 48 and in the lever 100, constantly biases the upper end of the lever to its operating position over the flanged lower end 94 of the sleeve 92.

The driver 70, during a stroke thereof, sinks the drive screw or nail 20 to the proper depth into the insole of the shoe 18. Downward displacement of the driver 70 in a passage 110 of the spindle is limited by a key 112 (FIG. 4) extending through a slot 114 in the wall of the spindle and lying in a keyway 116 extending longitudinally along the lower portion of the driver. The key 112 lies in a recess 118 which is formed in the guide block 48 and has formed in it a vertical slot 120 through which passes screws 122 which are threaded into the guide block and normally force the key against the bottom of the recess 118 to secure said key in a desired position on the guide block. Initial adjustment of the key 112 is effected to vary the starting position of driver 70 for the accommodation of drive screws or nails of different lengths.

When the carrier 28 and, therefore, the work supporting member or jack 22 are located in the upper work receiving position, the spindle 42 is fixed against depression by the engagement of a stud 130 (FIG. 13) located in the foot 84 by a hook-shaped extension 132 of a pivotal block 134 (FIGS. 9, 13, 14 and 16) mounted on one of the bearing pins 50 interposed between a portion of the carrier 28 and the guide block 48. The block 134 has a cam surface 136 located on an extension thereof disposed on the opposite side of the pivot point determined by the bearing pin 50 from the hook-shaped extension 132.

When the jack 22 is pivoted into operative position by the drive means, as hereinafter described, the hook-shaped extension 132 of the block 134 is pivoted out of contact with the stud 130 by a rod 138 slidably mounted on the carrier 28 in mounting members 140, 142 and engageable at opposite ends thereof with the cam surface 136 on the block 134 and a cam plate 144 mounted on the hood 14. The hook 132 is normally retained in contact with the stud 130, when located in the work receiving position as illustrated in FIG. 16, by a spring 150 opposite ends of which are attached to a stud 152 secured to the top of the block 134 and to a stud 154 secured to the mounting member 140. The rod 138 contacts the cam plate 144 during the pivotal movement of the carrier into operative position due to the arcuate path followed by the carrier and the members thereon and the end thereof in contact with the cam surface 136 is urged outwardly relative to the cam plate 144 thereby releasing the stud 130 from the hook 132 when the jack is in operative position, as illustrated in FIG. 9.

When the carrier 28 is in the operative position, depression of the spindle 42 is limited by the contact of a stud 160 mounted in the foot 84 with the lower surface of a slot 162 cut in a block 166 mounted on one of the bearing pins 50 interposed between a portion of the carrier 28 and the guide block 48 on the opposite side of the guide block 48 from the block 134. As stated above, the foot 84 and spindle 42 are urged upwardly by the spring 80 and normally retained in an upper position thereby.

Formed in the upstanding housing portion 45 of the carrier 28 is a vertical cylinder 168 in which operates a tubular piston 170 having at its upper end an enlargement provided with a spherical depression 172 shaped to receive a complementary lower surface of a bed piece 174 having a planar upper face adapted to support the last by contact with the crown or upper surface of the back cone thereof. The lower portion of the cylinder 168 is closed by the plate 176 secured thereto. The bed piece 174, the cylinder 168 and the piston 170 collectively constitute the mount 44. Depression of a hold-down

member 180 mounted on the head 14 into contact with a heel of a shoe mounted on the jack 22 initially causes the bed piece 174 to tilt to the proper angular position and then after clamping pressure is applied to the bed piece, as hereinafter described, to be held against displacement on the piston 170 due to the spherical shape thereof.

The bed piece 174 has a radial slot 182 (FIG. 10) through which the spindle may pass in certain angular positions. The piston 170 and the bed piece 174 are normally urged upwardly by a pair of expansion springs 184 surrounding rod 186 which are secured to the upper end of the piston 170 and pass through bores 188 in the carrier 28. Upward movement of the piston 170 is limited by contact of nuts threaded onto the rods 186 with the underside of the carrier 28. The piston 170 and, therefore, the bed piece 174 are freely movable in the cylinder 168 when the jack 22 is in the work receiving position thereby permitting adjustment of a last on the spindle and bed piece.

In order to insure that the portion of the crown of the back cone of the last 40 or 79 overlying the slot 182 of the bed piece is effectively supported there is provided a slide plate 190 which is movable along a forwardly and rearwardly undercut guideway 192 in the planar upper face of the bed piece and which has formed in it a hole 194 through which the spindle 42 passes freely. In accommodating the last 79 the bed piece 174 may be initially oriented slightly on the tubular piston 170, the upper face of the bed piece during such orientation being inclined slightly downwardly and rearwardly from the horizontal. The bed piece 174 is provided at its forward lateral portions with flanges 196 which are normally in engagement with the flanged upper face of the tubular piston, the upper face of the bed piece at this time being horizontal. The flanges 196 allow the bed piece 174 to tilt slightly backward from its horizontal position to accommodate slight variations in the angles of the last passages and/or irregularities in the crowns of the back cones of the lasts but prevent the operator from tipping the forward end of the bed piece 174 downwardly thereby preventing such movement when the last is removed and ensuring the proper location of the bed piece to facilitate positioning of the next last.

The consistent accuracy of the thimble hole 90 and the extension thereof make it unnecessary to provide an initially tiltable bed piece when operating on shoes mounted on lasts of this type and, accordingly, the bed piece may be rigidly secured in its horizontal position to the piston 170 or may be formed integral with said piston. In the illustrated construction it will be noted that when the spindle 42 is in its vertical position, the vertical axis of the thimble is disposed at a substantial distance rearward of the vertical axis of the tubular piston 170 and accordingly downward pressure imparted to the slide plate 190 and to the upper face of the bed piece 174 has a tendency to tilt the rear end of the bed piece downwardly against its locking action in the tubular piston 170. With the foregoing in view the rear end of the flanged upper portion of the tubular piston 170 has secured to it by screws 198 a block 200, the construction being such that when the machine is adjusted for thimble hole work the slide plate 190 rests upon the upper surface of the block, the flanges 196 of the bed piece 174 at this time resting on the upper face of the tubular piston 170. Accordingly, when operating upon thimble hole work the bed piece 174 is fixed against tilting on the tubular piston 170.

The lower end of the piston 170 has secured to it a valve seat 204 in an axial extension of which a stem of a valve 206 is movable. An expansion spring 208 tends to close the valve 206 and thus the passage through the piston 170. When this occurs the piston is locked against depression by oil in the cylinder 168.

When the jack 22 is in its work receiving position, the valve 206 is held open by a multipart bell crank lever 210

(FIGS. 12 and 15) fulcrumed on the enlargement of the piston 170, a bifurcated arm 211 of the lever extending between flanges on a stem of the valve 206. The bell crank lever 210 has a depending arm 212 past which a cam rod 214 moves in contact therewith during the pivotal movement of the carrier 28, said cam rod being slidingly mounted on the carrier in mounting members 216, 218 and engageable at one end thereof with the cam plate 144 mounted on the hood 14. The cam rod 214 has an enlarged cam surface 220 mounted thereon on the end opposite that engageable with the cam plate 144. The cam rod 214 is normally urged to the right as viewed in FIG. 9 relatively to the arm 212 by a spring 222 interposed between the mounting member 216 and a collar 224 secured to the cam rod, a terminal position of said collar being determined by contact thereof with the mounting member 218. When the carrier 28 is in the work receiving position, the collar 224 is urged into its terminal position and the depending arm 212 of the bell crank lever 210 engages the enlarged end portion of the cam surface 220 which has a greater diameter than the cam rod 214 thereby causing the valve 206 to be lowered from its seat due to the pivoted position of the bell crank lever. Pivotal movement of the carrier 28 into operative position brings the cam rod 214 into contact with the cam plate 144 and the cam surface 220 is urged out of contact with the arm 212 thereby permitting the spring 208 to close the valve 206. The piston 170 and the bed piece 174 are thus locked in position when the carrier is in the operative position and free to move when the carrier is in the work receiving position. The alternate positions of the arm 212 are illustrated in FIG. 15.

The holdown member may be of the type disclosed in United States Letters Patent No. 1,545,575, granted July 14, 1925, to John F. Standish, and application for Letters Patent of the United States Serial No. 142,172, referenced above, comprising a tread abutment and a back fork operatively connected for cooperative movement. The holdown member 180 illustrated in FIGS. 1, 3, 5 and 7 is described in the above-mentioned application as an alternative design adapted for use with high style Louis heels. Preparatory to operating upon the work, the holdown member 180 must be adjusted in relation to the jack 22 to accommodate the particular style of heel to be attached, said adjustment being made as described in the above-mentioned patent and application.

Pivotal movement of the carrier 28 is controlled by a two-way piston 230 (FIG. 17) housed in a cylindrical housing 232 (FIGS. 3, 4 and 5) mounted on a bracket 233 pivotally secured to a support member 234 mounted on the frame 12. The movement of the piston 230 is translated to the carrier 28 through a piston drive rod 236 pivotally secured to the rear of the carrier 28. The piston 230 and, therefore, the carrier 28 are normally retained in an upper position by fluid pressure applied to the bottom of the piston 230 through a line 238 and controlled by a valve 240 (FIG. 17). Downward displacement of the piston 230 is initiated by depression of a treadle 242 (FIG. 3) pivotally mounted on a cylindrical piston housing 244 secured to the base member 10. The treadle 242 is normally retained in an upper position, as illustrated in FIG. 3, by a spring 246 opposite ends of which are secured to a portion of the treadle displaced from the pivot point thereof and to a bracket 245 mounted on the frame 12. The upper position of the treadle 242 is determined by contact thereof with a stop screw 248 mounted in a bracket 249 secured to the frame 12. The initial depression of the treadle 242 releases a valve 250 mounted on the frame 12, as illustrated in FIG. 6, said valve controlling the introduction of pressure fluid to the upper portion of the cylinder 232 through a line 251. The rate at which the piston 230 is depressed and returned is regulated by a speed control valve 252.

Movement of the head 14 is controlled by a two-way piston 256 (FIG. 17) housed in a cylindrical housing 258

(FIG. 8) and a one-way piston 260 housed in the housing 244, the housing 253 being mounted on a drive rod 262 secured to the piston 260. The head 14 is slidably mounted in the frame 12 for movement toward and away from the jack 22, movement being imparted to the head 14 by the pistons 256 and 260 through a pair of rods 264 (FIG. 1) opposite ends of which are secured to the head at 256, 268 and to lateral extensions 270 of a housing 272 to which a piston drive rod 274 of the piston 256 is secured. The rods 264 are slidably mounted in support members 276, 278. The piston 256 controls the movement of the head between an upper position and an intermediate position wherein the hold-down member 130 is immediately above the jack and a shoe thereon in position to engage a heel on said shoe. The piston 260 is employed to move the head from said intermediate position into a position wherein the hold-down member engages and clamps the heel on the shoe.

The piston 260 is normally retained in an upper position by springs 280 opposite ends of which are secured to the lower portion of the support member 278 and to a flange 282 secured to the piston drive rod 262 and the piston 256 is normally retained in an upper position by fluid pressure applied to the bottom thereof through a line 284 and controlled by a valve 286 (FIG. 17). The head 14 is thus normally retained in the upper position when the machine is in use. When the carrier 28 is pivoted into operative position by the initial depression of the treadle 242, a contact member 288 (FIG. 4) secured to the carrier 28 depresses a valve 290 mounted on the support member 234 thereby initiating the application of fluid pressure to the upper surface of the piston 256 through the line 292. The rate at which the piston 256 is depressed and returned is regulated by a speed control valve 294. As stated above, depression of the piston 256 is translated through the piston rod 274, housing 272, and rods 264 to the head which is lowered to the intermediate position defined above. When the head is in the intermediate position, the operator can examine the alignment of the hold-down member with the heel of the shoe mounted on the last and correct any deviations or release the treadle to return the head and carrier in the event deviations exist which cannot be corrected in the intermediate position.

The hold-down member 130 on the head 14 is moved into engagement with the heel of a shoe by further depression of the treadle 242. When the treadle is fully depressed, it contacts a plunger on a hold-down control regulator 300 thereby initiating the application of fluid pressure to the upper surface of the piston 260. Depression of the piston 260 is translated to the cylinder 258 and the connecting members appurtenant thereto through the drive rod 262 threaded into a cam 302 which is secured to the lower portion of said cylinder and, thus, results in depression of the head 14. When difficulty is encountered in the application of pressure to a heel, the operator can raise the head to the intermediate position by releasing the treadle from contact with the plunger of the regulator 300. The piston is returned to its intermediate position by the springs 280. The maximum hold-down pressure is controlled by the regulator 304.

When the hold-down member has clamped the heel on the shoe mounted on the jack 22, pressure is built up within the system illustrated in FIG. 17 and, particularly, in an accumulator 310 mounted in the support member 278. A regulator 312 controls the pressure within the accumulator 310. When the pressure has reached a predetermined magnitude required to drive a nail into the heel, a sequence valve 314 opens a drive operating valve 316 thereby releasing the pressure fluid within the accumulator into the cylinder 272 to drive a piston 318. The piston 318 has a flanged upper portion 320 (FIGS. 4, 5 and 7) overlapping the edge of the cylinder 272 into which a plunger 322 is threaded. The plunger 322 contacts the rod 70 and drives the nail as a result of the dis-

placement of the piston 318 by the fluid pressure applied from the accumulator. The throw or displacement of the piston is determined by the contact of a shock absorbing member 324 secured to the flanged portion 320 with the lower inner surface 325 of an annular member 326 which is threaded into the support member 234. The outer periphery of the annular member 326 has gear teeth thereon which cooperate with gear teeth located on an adjustment rod 328 thereby facilitating adjustment of the relative position of the member 326 and regulation of the throw of the piston and, therefore, the depth the nail is driven. A shut-off valve 340 is manually operative to prevent operation of the valve 316 and, therefore, the piston 318. A safety device is provided to prevent the driving of a nail when a shoe has not been placed on the jack 22 comprising the cam 302 and a cam operated valve 342 mounted on the frame 12 by a bracket 344. The valve 342 is so positioned that the cam 302 will not actuate it unless the hood is displaced a distance incompatible with the presence of a shoe on the jack, the hood being brought into engagement with the shoe by depression of the rod 262 by the piston 260. An interlock system (not shown) may be provided to prevent the depression of the piston 260 prior to the complete depression of the piston 256 when the treadle is initially depressed its full traverse by the operator.

In the operation of the machine, a shoe and a heel to be attached thereto are mounted on the jack 22 with the spindle 42 in position in the last passage, the mount 44 being movable to facilitate positioning of the last and the spindle fixed to establish the proper location thereof. The treadle 242 is then depressed slightly from its normal position to release the valve 290 and effectuate pivotal movement of the carrier 28. As the carrier is pivoted into position by the piston 230 the cam rods 138 and 214 are urged outwardly from the cam plate 144 to release the foot 34 and the arm 212 of the bell crank lever 210 thereby releasing the spindle and locking the mount in position. When the carrier 28 is in operative position, the valve 290 is depressed by the contact member 288 and the piston 256 lowers the head into an intermediate position in location for the hold-down member to engage the heel. The operator now fully depresses the treadle and the hold-down member engages the heel to clamp it on the shoe due to the depression of the piston 260 and pressure is thereafter built up with the accumulator and automatically applied to drive the nail.

Having thus described my invention, what I claim as new and desire to secure by Letters Patent of the United States is:

1. In a wheel attaching machine comprising a jack pivotal between a work receiving position and an operative position, means located on said jack for mounting a last bearing a shoe, said mounting means comprising a mount and a spindle, and means for retaining said spindle against movement and for permitting movement of said mount when the jack is in the work receiving position, the combination of means operative by the pivotal movement of said jack to free said spindle and retain said mount.
2. In a heel attaching machine comprising a jack pivotal between a work receiving position and an operative position, a last supporting spindle, and means for locking the spindle against movement when the jack is in the work receiving position, the combination of means operative by the pivotal movement of said jack to free said spindle.
3. In a heel attaching machine comprising a jack pivotal between a work receiving position and an operative position, and a mount for supporting a last, means controlling movement of said mount to permit movement thereof when the jack is in the work receiving position, the combination of means operative by the pivotal movement of said jack to regulate said control means to retain said mount.
4. In a heel attaching machine comprising a jack

11

holddown means movable toward and away from said jack, the combination of cam means operative by the pivotal movement of said jack to free said spindle and retain said mount, said cam means comprising a plurality of cam rods cooperative with retaining means located on said mount and said spindle, means responsive to the presence of said jack in operative position to move said holdown means toward heel-engaging position, means for moving said holdown means into engagement with said

5

12

heel to clamp the heel in position on the shoe, and means operative in response to the clamping of said heel to insert attaching means into said heel.
